FIG. 1

FIG. 2

FIG. 3

INVENTOR

BRUCE K. SLONNEGER

BY

Carl Bensd

HIS ATTORNEY

described herein is admirably adapted to fulfill the object primarily stated, it is to be understood that it is not intended to confine the invention to the one form or embodiment shown herein, for it is susceptible of embodiment in various other forms.

What is claimed is:

1. In a device of the class described, the combination of a supporting member for a stack of business forms upon which written entries are to be made; a receptacle to receive a stack of said forms, said receptacle formed on one end of said member and comprising a first section of said member formed upwardly at right angles to the face of said member, and a second section formed rearwardly on said first section, said second section being biased downwardly toward the face of said member to form a resilient means to releasably hold the stack of forms on the holder; and a combination cover and writing table slidably mounted on the main supporting member and movable between the said second section and the stack of forms when moved into closed position.

2. In a device of the class described, the combination of a supporting member for a stack of business forms upon which written entries are to be made; a receptacle to receive a stack of said forms, said receptacle formed on one end of said member and comprising a first section of said member formed upwardly at right angles to the face of said member, and a second section formed rearwardly on said first section, said second section being biased downwardly toward the face of said member to form a resilient means to releasably hold the stack of forms on the holder; and a combination cover and hand rest slidably mounted on the member to provide an adjustable cover for the stack of forms and a hand rest when making written entries on the forms, the forward end of said combination cover

and hand rest movable beneath the said second section when moved into closed position.

3. In a device of the class described, the combination of a supporting member for a stack of business forms upon which written entries are to be made; a receptacle to receive a stack of said forms, said receptacle formed on one end of said member and comprising a first section of said member formed upwardly at right angles to the face of said member, and a second section formed rearwardly on said first section, said second section being biased downwardly toward the face of said member to form a resilient means to releasably hold the stack of forms on the holder; and a combination cover, writing table, and hand rest slidably mounted on the member to provide an adjustable hand rest when making written entries on the forms, said combination cover, writing table, and hand rest provided with runways formed to slidably engage the sides of said member at the under side thereof, and extending forwardly over the top of said main supporting member and stack of forms, said combination cover, writing table, and hand rest being formed from one sheet of material.

BRUCE K. SLONNEGER.
